UNITED STATES PATENT OFFICE

ARTHUR W. ALTVATER, OF ST. LOUIS COUNTY, MISSOURI

MARKING MACHINE

Application filed December 13, 1928. Serial No. 325,704.

This invention relates to marking machines for making impressions upon leather and other materials for ornamental purposes, or to indicate the outlines for the guidance of 5 subsequent operations, or for any other purpose desired.

An object of the invention is to provide a machine for the purpose stated comprising 10 means for supporting the material or articles to be marked in different positions or at different altitudes above a base, and a manipulative die supporting device movable from position to receive a marking substance, such as ink, to a position to press upon the material to be marked and make an impression 15 thereon with the marking substance.

Another object of the invention is to provide a marking machine equipped with means for properly supporting, locating and holding 20 fitted shoe uppers in a position to receive the impressions from the marking device.

Another object of the invention is to provide a machine capable of operation upon fitted shoe uppers or upon flat work, as desired. 25

Other objects will appear from the following description, reference being made to the accompanying drawings in which,

Fig. 1 is a top plan view of my improved 30 machine.

Fig. 2 is a side elevation of the machine with a work support thereon for supporting fitted shoe uppers and the like, a part of the side of the machine being broken away to 35 show the balancing device.

Fig. 3 is a side elevation of the machine with the support thereon for flat work.

Fig. 4 is a sectional view of the die carrier and die plate.

Fig. 5 is a view showing a part of the die plate equipped with means for engaging the carrier and also showing the device that is supported by the carrier for engaging the die plate.

Fig. 6 is a perspective view of the work support shown in Fig. 2 which is designed and adapted for use in working upon fitted shoe uppers and similar work.

The supporting frame 1 of the machine 50 may, if desired, be in connection with legs

2 in order to support the frame at the proper height for convenient operation of the machine.

Upon the upper or rear portion of the frame a box-like member 3 is mounted, the 55 horizontal upper end wall 4 of the part 3 being enclosed within an upwardly extended marginal flange 5. The bottom wall 4 and the surrounding flange 5 forms a pan to contain a pad 6 that may be saturated with any fluid marking substance, such as ink. The part 3 may be rigidly secured to the frame 1 by bolts 7 extending through arms 8 projecting from said frame 1 and through arms 9 projecting laterally from the part 3. 60

A base 10 is mounted on the front of the frame 1 at the front side of the part 3 and has its upper surface in a plane lower than the pad 6. The base 10 is rigidly attached to the frame 1 by bolts 11 passing through ears 12 projecting from the frame 1 and through ears 13 projecting laterally from the base 10. This base 10 is designed and adapted to receive interchangeable work supporting gages 70 of different types and designs. One such work supporting gage is shown in Figs. 1 and 2 and is designed specially to support and position or gage shoe uppers and the like for operation of the marking mechanism. 75

This work supporting gage comprises a plate 14 having holes therethrough to receive dowel pins 15 rigid with and projecting upwardly from the base 10. A horizontal gage plate 16 is supported above the plate 14. The gage plate 16 has its rear edge detachably secured 80 to a block 17 by screws 17^a, which block 17 is rigid with the plate 14. The front edge of the plate 16 bears upon a post 18 which is in rigid connection with the plate 14. The post 18 is a relatively small supporting element. 85 This leaves all portions of the plate 16 laterally from the post 18 and in front of the block 17 spaced so that portions of the fitted shoe upper or other work may enter said

spaces while other portions of the shoe upper or other work are properly located upon the support 16 by gage elements 19. As shown, the gage elements 19 are in the form of pins which are designed and adapted to project through holes or openings in the 90 95 100

work. But, it is obvious that any appropriate type of gage elements may be used and that the invention is not restricted in this respect.

The die carrier 20 has its rear edge pivoted to the upper ends of arms 21, the lower ends of which are attached to a shaft 22 mounted for rocking movements in the walls of the part 13. The front edge of the die carrier 20 is pivoted to the upper ends of arms 23, the lower ends of said arms 23 being pivoted to the upper ends of projections 24 which are rigid with and extend upwardly from the frame 1 at the sides of the base 10 and considerably to the front of the part 3.

The under side of the die carrier 20 is formed with a recess 25 (Fig. 4) designed and adapted to receive projections 26 from the die plate 27. A clamping device 28 is rigid with the lower end of a stem 29 mounted for turning movements in the die carrier 20 and being operative to obtain clamping engagement with and to release the projections 26. The stem 29 projects upwardly through the die carrier 20 and is rigidly secured to a handle 30 above said die carrier, which handle is operative to turn the spindle 29 to obtain clamping engagement with the ears 26 or to release said ears, as desired. A pin 31 projecting from the die carrier into a notch 32 in a plate 33 that is rigid with the lower end of the handle 30 limits extent of turning movement of said handle but permits sufficient turning movement to obtain engagement with and to release the projections 26. In order to cooperate with the clamping devices described to prevent turning movement of the plate 27 with respect to the die carrier 20 said plate 27 is provided with one or more projections 34 spaced laterally from the projections 26 and designed and arranged to engage in holes 35 in the die carrier. Obviously, when the projection or projections 34 are engaged in the holes 35 and when the clamping device 28 is engaged with the projections 26 the plate 27 will be held clamped against the under side of the die carrier 20 and will be held from turning. The under side of the plate 27 supports a marking die 36. When the die carrier 20 is swung to the rear the marking die 36 contacts with and receives marking substance from the pad 6 so that when said die carrier is swung forward and downwardly the design of the die will be impressed upon the material, such as a shoe upper that is positioned upon the plate 6 by the gages 19. That is to say, a fitted upper can be conveniently applied to these gages because of the novel way in which the plate 16 is mounted and supported in spaced relationship so that the fitted upper may be draped about said plate. In this manner that portion of the upper which is to be marked with a design is above the plate and other portions draped down at the ends of the plate 16 and under said plate.

Obviously, since the plate 14 is removable

and interchangeable, such plates bearing different designs and arrangements of gages 19 may be used, as desired. And, since the plates 27 are removable and interchangeable, different designs of marking dies may be used. This is a highly important feature of this invention, as my machine is designed and adapted for a much wider range of use than machines in which these improvements do not exist.

In the same instances it may be desired to make impressions or designs upon or in flat work, such as flat pieces of leather. It is desirable, of course, that flat work be supported at the same height as fitted uppers or the like so that the extent of forward movement of the die carrier will be approximately the same for all classes of work. In order to support flat work at the same height as the supporting plate 16 I provide a removable platen 37, the vertical thickness of which is the same as the vertical distance from the under side of the plate 14 to the upper side of the plate 16. Thus when the platen 37 is placed upon the machine the upper side of said platen is in the same plane in which the upper side of the plate 16 is located when the equipment shown in Figs. 1 and 2 is used. The under side of the platen 37 is provided with holes to receive the dowel pins 15 and the side edges of said platen are provided with extended handles 38 to facilitate and expedite placement and removal of the platen. From the upper side of the platen 37 dowel pins 39 project. And the gage plates 40 having therein gages 41 are provided with holes to receive the dowel pins 39. Thus when the dowel pins 39 are projected through the holes in the gage plates 40 the said gage plates are necessarily thereby positioned so that the gages 41 are in position properly to guide and gage the location of the flat work upon the plates 40. Thus the gages 41 locate and position the work for proper operation of the die carrier. That is to say, backward and forward operation of the die carrier will result in making proper impressions, designs, outlines, or the like upon the flat work on the gage plates.

It is apparent that the handle 30 constitutes means for operation of the die carrier as well as means for operating the clamping and releasing device whereby the die plates 27 are secured to the die carrier. However, the machine may be otherwise operated, as, for instance, by a belt device 42 passing over a pulley or sheave 43 attached to the shaft 22 and provided with familiar treadle connections (not shown). In order to move the die carrier to and retain said die carrier in an appropriate starting position I provide springs 44 having connections 45 with a part of the member 3 and connections 46 with the shaft 22. The power and tension of this spring is utilized to support the die carrier 20 approximately in the position shown in Fig. 2 when

the machine is idle. That is to say, these springs support the die carrier above the gage devices at the front of the machine and also in a position in which the die is out of contact 5 with the pad 6. In this position the die carrier is intermediate the pad 6 and the position of the work to be operated upon.

From the foregoing it will be seen that I have provided a machine capable of application to various uses and designed and adapted 10 to operate upon different types and forms of work. For instance, the machine, as stated, will operate satisfactorily upon flat work and with equal satisfaction by use of the equipment shown in Figs. 1 and 2 will operate 15 upon fitted uppers of shoes or other work of that character without creasing the material. The feature of interchangeability of the dies and of the gage and work supports is of a 20 high degree of importance and these improvements are claimed broadly in this machine.

I do not restrict myself in any unessential effects but what I claim and desire to secure by Letters Patent is:—

25 1. A marking device comprising two members, means for supporting a marking device upon one of said members, and a support upon the other member having spaces arranged to receive parts of a fitted shoe upper while 30 another part of the upper is upon said support.

35 2. A marking device comprising two members, means for supporting a marking device upon one of said members, a support upon the other member having spaces arranged to receive parts of a fitted shoe upper while another part of the upper is upon said support, and means for operating the other one of said members to make impressions upon a portion 40 of the upper which is upon said support.

45 3. A machine of the character described comprising two members, a marking device in connection with one of said members, a support removably mounted upon the other member and having spaces at its lateral and under sides adapted to receive portions of a fitted shoe upper while another portion of the upper rests upon said support, a gage for positioning that portion of the upper which is 50 upon said support for operation of the marking devices, and means for operating said other member to cause said marking devices to make impressions upon that portion of the shoe upper that is upon said support.

55 4. A machine of the character described comprising a frame, a support removably mounted upon said frame and having spaces at its lateral and under sides adapted to receive portions of a fitted shoe upper while another portion of the upper rests upon said support, a movable member, a marking device in connection with said movable member, and means for operating said movable member to place said marking device into

contact with the portion of the shoe upper that is upon said support.

5. A marking machine of the character described comprising a frame, a support mounted upon said frame and having spaces at its lateral and under sides adapted to receive portions of a fitted shoe upper while another portion of the upper rests upon said support, a gage for positioning the shoe upper in proper position upon said support, and a marking device operative to make impressions upon that portion of the shoe upper that is upon said support. 70

6. A machine of the character described comprising two members, means for supporting a marking device in connection with one of said members, a support having spaces at its lateral and under sides adapted to receive portions of a fitted shoe upper while another portion of the upper rests upon said support, means for holding said support in proper position for the operation of said marking device, and means for operating the marking device to make impressions upon that portion 80 of the shoe upper that is upon said support. 85

7. A machine of the character described comprising a frame, a marking device supported by said frame, and means for supporting gages of different heights at the same distance above said frame in position to locate 90 work for operation of said marking device.

8. A machine of the character described comprising a swinging member, means for supporting a marking device in connection with said member, a frame, and a support upon said frame having spaces arranged to receive parts of a fitted shoe upper while another part of the upper is upon said support in position to receive impressions from 100 said marking device. 105

9. A machine of the character described comprising a swinging member, means for supporting a marking device in connection with said member, a frame, an element removably supported by said frame, means for holding said element in a predetermined position upon said frame, and a support upon said element having spaces at its lateral and upper sides adapted to receive portions of a fitted shoe upper while another portion of the upper rests upon said support in position for operation of said marking device. 110

10. A machine of the character described comprising co-acting members adapted to be closed one against the other, a removable pattern die carried by one of said members, and a removable gage carried by the other member and having spaces to receive parts of the work while another part of the work is upon said support in position for operation of said pattern die. 115

11. A marking machine comprising two members, a support upon one of said members having spaces arranged to receive parts of a fitted shoe upper while another part of 120 125 130

the upper is upon said support, and a marking device supported in connection with the other member and movable thereby to contact with that part of the shoe upper that is upon said support as aforesaid.

- 5 12. A marking device comprising two members, a support upon one of said members having spaces arranged to receive parts of a fitted shoe upper while another part of the upper is upon said support, a marking device supported by the other member, and means for operating said other member to contact said marking device with said shoe upper to make impressions upon a portion of
10 the upper which is upon said support.
